The ornamental design for a saw blade, as shown and described.

DESCRIPTION

FIG. 1 is a perspective view of a saw blade according to the present disclosure;

FIG. 2 is a front view of the saw blade of FIG. 1, the rear view of the saw blade is a mirror image of the front view; and,

FIG. 3 is a bottom view of the saw blade of FIG. 1, top, left and right side views are identical to the bottom view;

The broken line showing in all figures, of portions of the saw blade is for illustrative purposes only and forms no part of the claimed design.
